NEEDLE OPERATING MECHANISM

Filed Jan. 3, 1931

UNITED STATES PATENT OFFICE

ADOLF MAX MÜLLER, OF CHEMNITZ IN SACHSEN, GERMANY

NEEDLE OPERATING MECHANISM

Application filed January 3, 1931, Serial No. 506,451, and in Germany January 10, 1930.

My invention relates to warp knitting machines and more especially to improvements in needle actuating mechanism for machines of this type.

5 In the art of designing warp knitting machines having a straight knitting line it has common practice heretofore to cooperatively associate the thread guiding elements and the needles in such manner that the thread guides must pass between the needles and move laterally thereof, in order to present the threads to the needles in appropriate position for being engaged and the loops being formed.

10 Also with some types of circular warp knitting machines the thread guiding members are operated in substantially the same manner.

15 However as a matter of fact the proper engagement of the threads by the needle hooks with all these knitting machines offers peculiar difficulties known to practitioners: It has been attempted to overcome the said difficulties by giving the thread guiding members of circular warp knitting machines a so-called "Pilgerschritt" motion, which means, that the thread guiding members will recede a short way during each loop forming action and will be advanced in turn over a distance exceeding their retrogressive movement by one or more gauge units, so as to get away from the needles, while the latter are rising, and to bring the descending needles into the reach of hooks.

20 In order to properly perform these movements however rather complicated actuating mechanisms are required which seriously increase the cost of production, operation and upkeep of machines of these classes. Moreover the knitting machines are bodily subjected through the actuating mechanisms concerned to rather hard shocks and concussions in quick succession and must be worked necessarily at a reduced speed.

25 The principal object of my invention is to overcome the said drawbacks by providing an improved needle actuating mechanism for warp knitting machines which is composed of relatively few parts of simple design, easily to be assembled and disassembled.

30 Other objects of the invention and ad-

vantages attained by the same will become apparent hereinafter.

The nature and scope of the invention are briefly outlined in the appended claims and will be more fully understood by the following specification taken together with the accompanying drawing, in which

35 Fig. 1 is a fragmentary view showing the needle cylinder and the needle actuating mechanism of a circular warp knitting machine by way of an example in cross section, the needles being in their uppermost position.

40 Fig. 2 diagrammatically shows the crossed threads and the needles, the latter being in their uppermost position corresponding to that of Fig. 1.

45 Fig. 3 is a fragmentary view showing the needle cylinder and the needle actuating mechanism in cross section, the needles being in an intermediate position and also in their lowermost position, indicated by dash and plain lines respectively.

50 Fig. 4 diagrammatically shows the crossed threads and the needles, the latter being in their lowermost position which corresponds to that of Fig. 3.

55 Fig. 5 is an another diagram showing the crossed threads and the needles, the latter being in an intermediate position.

60 Fig. 6 is a side elevation of a knitting needle.

65 According to this invention means are provided for imparting to the knitting needles in addition to their up- and downward movement a reciprocating tilting motion in the direction towards and away from the warp threads and in a manner described hereinafter with reference to Figures 1-5 of the drawing:

70 In a collar, projecting from the needle cylinder 1 of the knitting machine slots or notches 2 are formed which represent guide members for the needles 3. The latter are adapted to move up- and down relatively to the needle cylinder 1 and simultaneously to be tilted towards and away from the center of the needle cylinder 1, as indicated in plain and dotted lines in Figs. 1 and 3.

75 For this purpose the needles 3, which are formed as usual with a hook 3b at their up-

per end, are provided with a heel portion of peculiar shape at their lower end, having working faces $3a$, $3c$, $3d$, $3e$ as seen in Figs. 1, 3 and 6.

5 The needles 3 are supported and operated by a cylindrical member 4 which is given a reciprocating movement in vertical direction through actuating rods 8 and by a driving mechanism—not shown. The cylinder 4 is 10 formed with an annular groove 5 located at the rear of a front wall 6 and is provided with a crown plate 7 detachably mounted thereon by means of clamping screws 10. At the circumferential edge of the said crown plate 7 slots 9 are formed, by which the needles 3 are guided.

15 It will be noted that the guiding slots 9 are formed with inclined rear faces $9a$, the inclination of the latter substantially corresponding to that of the working faces $3e$ of the needles intermediate their shank and heel portion.

20 The operation of the needle actuating mechanism described is as follows:

25 The needles 3, individually designated by the letters a , b , c , d , e , f , g , in Figs. 2-5, on having been moved into their uppermost slightly tilted position, shown in Figs. 1 and 2, in which the needle hooks $3b$ are displaced 30 towards the center of the needle cylinder 1—are supported by the actuating cylinder 4, the working face $3c$ of the heel of the needles being engaged by the upper face of the front wall 6 of the actuating cylinder 4.

35 As soon as the latter begins to descend its front wall 6 becomes disengaged from the heel of the needle while the inclined rear faces $9a$ of the slots 9 of the crown plate will engage the inclined working faces $3e$ of the needles, thus causing the latter to be tilted into a practically vertical position as shown in dotted lines in Figs. 1 and 3—but not to descend yet.

40 During this operation the needles 3 are guided at their upper end within the slots 9 of the needle cylinder and are held in frictional contact with the latter by the loops of the knitted fabric which rest under tension upon the top edge of the needle cylinder 1,— 45 as seen in Fig. 1.

45 The hook $3b$ of the needles has thus been brought into a position directly above the crossing point k of the upper and lower row threads 1-7.

50 Thereupon—while the needle actuating cylinder 4 continues to descend—its crown plate 7 will engage the upper working face $3d$ of the heel of the needles, causing the latter likewise to descend until they reach their lowermost position, shown in plain lines in Fig. 3. Meanwhile the hook $3b$ of the needles has reached the threads at their crossing points k , which are specially marked in Fig. 2, so as to pull the threads through the loops 55 m of the knitted fabric, resting on the top

edge of needle cylinder 1, and to form a new loop as indicated in Figs. 3 and 4.

55 Thereafter the needle actuating cylinder 4 begins to rise, and its crown plate 7 will thus become disengaged from the working face $3d$ of the heel of the needles, while the front wall 6—in sliding along the inclined working face $3a$ of the heel—gradually tilts the needles into an inclined position and eventually comes into contact with the working face $3c$ of the heel, causing the needles likewise to rise, until they reach their uppermost position shown in plain lines in Fig. 1.

60 The operations described above follow each other in due sequence so as to form a cycle of 80 movements.

65 It should be noted that the needles 3 while rising are in an inclined position in which the needle hooks are beyond the crossed threads, i. e. in a position sufficiently wide 85 apart from the latter so that they cannot come into touch with the threads.

70 While the needles 3 are rising and descending each set of the thread guiding rings $O-u$, designated by the numbers 1-7 in 90 Figs. 2, 4, 5 is displaced in the direction of the arrows to the right and to the left respectively over a distance equal to one needle gauge unit.

75 When compared with the specific position 95 of the thread guides O and U , shown in Figs. 1 and 3 and representing the "zero" position, the thread guides have been shifted in Fig. 4 over a distance equal to one half 100 needle gauge unit to the right and left respectively, after the needles a , b , c , d , e , f , g have knocked over their old loops and have formed new ones.

80 Thereafter the rising needles a , b , c , d , e , f , g will pass through the gaps between the 105 threads underneath the crossing points; for instance needle c has to pass through the gap, cross hatched in Fig. 4, between the threads of the upper thread guides 2, 3 and the lower thread guides 4, 5. The needles will not come into contact with the crossed threads until having reached their upright position, indicated in dotted lines in Fig. 1.

85 Briefly summarizing the salient features 110 of my invention and the advantages obtained by the latter: Means are provided for tilting the needles—prior to their rising motion—so that the upper section of the needles will extend beyond the top edge of the needle bed or knockover comb and will—while 115 rising—evade the threads.

90 On descending the needles are tilted towards the threads so that the needle hooks will come into a position directly above the threads and will securely get hold of the latter.

95 It should be noted that the mechanism for lifting and lowering the needles is designed so as to simultaneously effect their tilting movements,—and that no additional device

or attachment is required for this latter manipulation.

This advantage is obtained by providing the lower section of the needles with a heel portion of special design and cooperatively associating with the latter needle actuating means of special design.

Various changes and modifications may be made in the design of needle operating mechanisms of the type and for the purpose set forth, and in the shape and cooperation of their component parts without substantially departing from the spirit and the salient ideas of my invention.

15 For instance the crown plate 7 which is provided with guide slots 9 for the needles 3 may be made of a plurality of separate pieces in order to facilitate the exchange of needles wherever required.

20 Needle operating mechanism having the features shown and described above with reference to circular warp knitting machines may be applied to and used to equal advantage in connection with straight warp knitting machines, also with other types of knitting machines for warp fabrics in which the needles are singly actuated or in groups or are all united and jointly manipulated by one and the same common needle carrier.

25 Latch needles may be used instead of barbed needles to equal advantage in connection with needle operating mechanism for warp knitting machines, designed according to this invention.

30 What I claim is:

1. In a needle operating mechanism for the purpose set forth the combination with needles which are provided at their lower end with a heel portion, the latter presenting two working faces extending substantially vertical to the main shank of the needle and two other working faces in inclined position relatively to the needle shank, of a needle actuating member having a groove and a crown plate, the front wall of said groove and the said crown plate having working faces which are cooperatively associated with the heel and shank of the needles, a needle bar presenting needle guiding slots, and of means for reciprocating the said needle actuating member relatively to the needle bar.

35 2. In a needle operating mechanism for warp knitting machines, means for lifting and lowering the needles relatively to the needle bed adapted to simultaneously tilt the needles toward and away from the warp threads, and the combination with the needles which are provided at their lower end with a heel portion, the latter presenting two working faces extending substantially vertical to the main shank of the needle and two other working faces in inclined position relatively to the needle shank, of a needle actuating member having a groove and a crown

plate, the front wall of said groove and the said crown plate having working faces which are cooperatively associated with the heel and shank of the needles, a needle bar presenting needle guiding slots, and means for reciprocating the said needle actuating member relatively to the needle bar.

3. In a warp knitting machine, the combination with a plurality of needles, each having a heel portion at its lower end, said heel portion having two working faces extending substantially at right angles to the length of the needle, and two inclined working faces, and means cooperating with the working faces to raise and lower the needles and impart an inclined position to the needles during the cycles of operation of the needles.

4. In a warp knitting machine, the combination with a plurality of needles, each having a heel portion at its lower end, said heel portion having two working faces extending substantially at right angles to the length of the needle, and two inclined working faces, and an actuating cylinder having a crown plate cooperating with the working faces to raise and lower the needles and impart an inclined position to the needles during the cycles of operation of the needles.

5. In a needle operating mechanism for the purpose set forth, the combination with needles which are provided at their lower end with a heel portion, the latter presenting two working faces extending substantially vertical to the main shank of the needle and two other working faces in inclined position relatively to the needle shank, of a needle actuating member having a groove and a crown plate, the front wall of said groove and the said crown plate having working faces which are cooperatively associated with the heel and shank of the needles.

In testimony whereof I have signed my name to this specification.

ADOLF MAX MÜLLER.
